a corporation of Ohio

Application July 16, 1935, Serial No. 31,641

6 Claims. (Cl. 92—43)

This invention relates to paper making apparatus.

One object of the invention is the provision of a paper pulp stock tank, or mix box, having provision for thoroughly intermixing the stock supplied thereto and providing uniformity of the product which is supplied to the stuff pipe which carries the stock to a paper forming screen or the like.

Another object of the invention is the provision of a mix box having baffle means which give abrupt changes in direction of flow of the pulp stock in its passage through the mix box, and which is so arranged as to withdraw the air from the stock before the stock travels to the stuff pipe.

Another object of the invention is the provision of a mix box having an air collector provided at a low point and adjacent the end of the stuff pipe or outlet passage, the air collector being so arranged as to cause a stock flow approximately horizontally as the stock moves to the stuff pipe, so that air is extracted.

Other objects and advantages of the invention will be apparent from the following description, the appended claims and the accompanying drawings, in which—

Fig. 1 is a top plan view of a paper making apparatus embodying the present invention;

Fig. 2 is an end elevation of the apparatus shown in Fig. 1; and

Fig. 3 is a side elevation of the paper making apparatus.

Referring more particularly to the drawings, 10 generally represents a cylinder mold, of any suitable construction, and preferably embodying a rotatable forming screen 11 arranged so that its greater portion is submerged in paper pulp stock contained in the vat 12. The stock flows to the vat through a supply passage or stuff pipe 13 which leads to a feed hopper 14 provided under the vat, in communication at its larger end with the stock supply compartment 15. The stock flows from the compartment 15, which has a width substantially corresponding to the length of the 20 forming screen, over a dam 16 and then into the vat proper, the paper pulp being deposited on the rotatable forming screen, and the white water, which flows into the screen, being collected in the white water chambers 17, communicating with one another by means of pipe 18. The 25 white water is returned through pipe 19 and pump 20, driven by motor 21, and passes through the pipe 22 and then back to the mix box which is designated generally by the reference number 24.

The mix box is supplied with paper pulp stock through a suitable supply pipe 25, and is adapted to thoroughly mix the comparatively thick pulp stock received through the pipe 25 and the white water which is returned through the pipe 22, and for supplying the mixed stock to the supply pipe 13. 5

In the usual mix box construction that has been previously used, the stock flows from the top of the mix box direct to the outlet pipe. In 10 doing so the stock velocity increases as it flows downwardly and the stock carries with it considerable air which cannot be eliminated due to the increasing speed of flow of the stock. Furthermore, in the usual form of mix box, there has 15 been considerable trouble because of poor distribution of the stock and white water. The result has been that the sheet does not form level in the vat, due in part to the incomplete mixing of the white water and the thicker stock supplied 20 to the mix box, and also due to the presence of air in the stock which causes considerable commotion in the cylinder mold. The air bubbles present in the stock at the time the stock is deposited on the forming screen will produce an 25 uneven surface of the formed sheet, as the air bubbles act as though miniature explosions were occurring in the stock while the fibers are being deposited. And if the vat is not properly arranged the commotion produced by the air in the 30 stock will be sufficiently violent to throw or spatter some of the stock all the way up to the sheet on the bottom side of the felt as the stock rises in the supply compartment 15.

In accordance with the present invention the 35 mix box is so arranged as to effectively intermix the white water and the thicker stock supplied to it, and also arranged to withdraw air from the stock before the stock passes into the stuff pipe 13. As shown in Figs. 2 and 3, the mix box preferably comprises a chamber having a plurality of baffles 27 and 28 which effectively divide the mix box into a receiving compartment 29, an intermediate compartment 30 and a supply compartment 31. Compartments 29 and 30 are in communication with one another at a low point, and compartments 30 and 31 communicate with one another near their upper ends so that the stock is compelled to flow downwardly through the 40 compartment 29, upwardly through compartment 30 and downwardly through compartment 31. The abrupt changes in direction of the stock flow, and especially at the point where the stock flows over the partition 28, provides for the re- 45 50 55

lease of some contained air, and is also effective in intermixing the stock.

To provide for more effective discharge of air and more effective intermixing of the stock, the mix box is provided, just above the discharge opening 33, with a wall or partition 34, serving as an air collector and also serving, as will be later described, to divide the flow from the main body of stock in the mix box into a number of different rapidly moving streams flowing towards one another and intersecting and striking one another to provide for thorough intermixing of stock. It is preferably dome-like in shape, having its lower side open and spaced some little distance above the bottom of the mix box by arms or brackets 35 which support the dome in place. Extending upwardly from the top of the air collector 34 is a vent pipe 37, placing the space just below the dome 34 in communication with the outside air at a point above the stock level 38. At the top of the pipe 37 there is preferably an indicating means to show the operator that the device is in operating condition and that the air is being eliminated. Such a device may comprise a light ball 39 placed at the top of the pipe 37, and sufficiently light in weight to be displaced by the air flowing up through the pipe 37.

The air collector or dome 34 operates to deflect the stock which moves downwardly in the compartment 31 of the mix box, so that the stock is caused to move out toward the walls of the mix box, the flow then changing abruptly in direction and passing under the dome 34 in an approximately horizontal direction as it flows inwardly toward the center of the opening 33 from all directions. This action produces a very thorough intermixing of the stock so as to supply a uniform product to the stuff pipe 13. As the stock flows toward the center of the mix box outlet 33, there is a liberation and collection of air just before the stock flows into the stuff pipe, the air being eliminated through the air pipe 37, producing a bobbing movement of the ball 39 which thus gives an indication to the operator that the device is properly functioning.

The air pipe 37 is preferably employed in conjunction with the wall 34, so as to provide for the removal of air that is liberated at a point just below the wall 34 where the stock is instantaneously almost at rest before starting its downward travel into the stuff pipe 13. However, even if the air pipe 37 were not present, the wall 34 would be effective in giving a very thorough intermixing of the stock because it serves to divide the main body of stock just above it into what may be considered a great number of streams flowing radially towards one another in all directions just below the wall 34 and just before entering the stuff pipe 13. These intersecting streams serve to prevent or interrupt any possible stratification and break up the flowing stock and provide for thorough intermixing of different portions with one another.

While the form of apparatus herein described constitutes a preferred embodiment of the invention, it is to be understood that the invention is

not limited to this precise form of apparatus, and that changes may be made therein without departing from the scope of the invention which is defined in the appended claims.

What is claimed is:

1. In paper making apparatus, a mix box for paper pulp stock comprising a receiving compartment, an intermediate compartment communicating at a low point with a low point of said receiving compartment, and a supply compartment 10 communicating at its upper end with an upper portion of said intermediate compartment, and a stuff pipe for supplying the stock to a forming screen, said stuff pipe extending from the lower end of said supply compartment, and an air withdrawal device in said mix box adjacent the end of said stuff pipe. 15

2. In paper making apparatus, a mix box, a forming screen, and a stuff pipe extending from said mix box for supplying paper pulp stock to 20 the forming screen, said mix box having baffle means producing an abrupt change in the direction of flow and providing for downward movement of the stock toward the stuff pipe, and means at a low point in the mix box for collecting 25 air from the stock as the stock travels toward the stuff pipe.

3. In paper making apparatus, a mix box for paper pulp stock, said mix box having a stuff pipe 30 extending from a low point thereof, and an air collector having its lower side open and located adjacent to and above the stuff pipe end but well below the stock level in the mix box, and means venting said air collector for the discharge of air therefrom. 35

4. In paper making apparatus, a stuff pipe, a mix box for supplying paper pulp stock to said stuff pipe, means for supplying paper pulp stock to said mix box, means for returning white water to the mix box, and means in said mix box for 40 collecting and eliminating air from the stock below the stock level and just before the stock passes into the stuff pipe.

5. In paper making apparatus, a mix box for paper pulp stock, said box having an outlet passage at a bottom portion thereof, and means closely adjacent said outlet opening forming a baffle for abruptly changing the direction of stock flow just preceding the entrance of the stock into the opening, said baffle having a downwardly facing chamber providing for the withdrawal of air from the stock at that point. 45 50

6. In paper making apparatus, a mix box for paper pulp stock, said box having a discharge opening and having baffle means for abruptly 55 changing the direction of flow of stock through the mix box and providing for downward flow of stock toward the discharge opening, an air collecting chamber having a downwardly facing air inlet opening adapted to receive air from the 60 stock and located near the bottom of the mix box and in the path of movement of the stock flowing downwardly and toward the discharge opening, and means for relieving air from said chamber. 65
